UNITED STATES PATENT OFFICE

172,005

HANDBAG

Belle Collis, Chicago, Ill.

Application May 21, 1953, Serial No. 25,153

Term of patent 7 years

(Cl. D87—3)

To all whom it may concern:

Be it known that I, Belle Collis, a citizen of the United States, residing at Chicago, in the county of Cook and State of Illinois, have invented a new, original, and ornamental Design for a Handbag, of which the following is a specification, reference being had to the accompanying drawings, forming part thereof.

Fig. 1 is a front perspective view of a handbag, showing my new design;

Fig. 2 is an enlarged section on the line 2—2 of Fig. 1; and

Fig. 3 is an end view.

The rear portion is identical with that shown in Fig. 1 with the exception of the latch closure member.

I claim:

The ornamental design for a handbag, as shown and described.
